WINDING MACHINE

Edward J. Abbott and Winthrop L. Perry, Wilton,
N. H., assignors to Abbott Machine Company,
Wilton, N. H., a corporation of New Hampshire

Application May 28, 1943, Serial No. 488,872

5 Claims. (Cl. 242—32)

This invention relates to filling winding machines of the type having a plurality of winding spindles or units and relative motion between the winding units and a part of or place in the machine at which the winding units are successively tended. Machines of this type are described and claimed in United States Patent No. 2,160,810, and in application Serial No. 386,136, filed March 31, 1941. This invention is particularly applicable to the preferred form of such machines in which a plurality of filling winding units are moved in a procession during winding, this procession passing automatic mechanism adapted to replace the wound package on each unit with a new empty core and start the winding of a fresh filling wound package on such new core as the unit passes, such machines being shown as preferred embodiments of said patent and said application Serial No. 386,136.

Among the objects of the invention are to simplify and improve the mechanism for producing the filling wind on the several units of the machine; particularly to simplify the construction of each of the several winding units; to simplify and improve the mechanism for determining the progressive shifting of zones of traverse of the thread traversing means of the several units; and to utilize for this purpose the relative traveling movement between the winding units and other parts of the machine.

Other objects of the invention and features of advantage and utility will be apparent from this specification and its drawings wherein the invention is explained by way of example.

In the drawings:

Fig. 1 is a plan view of a traveling spindle winding machine having the present invention applied thereto, this view being simplified by the removal of numerous parts not directly involved in this invention and by the omission of all except two of the numerous traveling winding units of the machine;

Fig. 2 is a right end elevation of the machine of Fig. 1 with certain parts broken way, and partly in section and with all excepting one of the winding units omitted;

Fig. 3 is a fragmentary plan view, partly diagrammatic, and with numerous parts omitted, showing four of the winding units of the machine at the place where the bobbins are changed and the winding started on the winding units in succession;

Fig. 4 is a plan view of one of the winding units of a machine, on a larger scale, with its winding package partly finished;

Fig. 5 is a side elevation of the winding unit of Fig. 4;

Fig. 6 is a fragmentary vertical sectional view, taken on the line 6—6 of Fig. 4;

5 Fig. 7 is a fragmentary view showing the thread guide assembly, taken on the line 7—7 of Fig. 6; and

Fig. 8 is a fragmentary vertical section of the friction slider element of the thread guide assembly and the reciprocating rod for driving the latter, taken on the line 8—8 of Fig. 7.

The winding machine, as to its general organization and construction of frame, winding unit conveying means, and winding unit tending mechanism, may be substantially the same as shown in said application Serial No. 386,136.

Thus the machine is shown as having a suitable guideway comprised of upper and lower rails 11 and 12 (Fig. 2) which define opposite

20 straight and semi-circular runs (Fig. 1) for the winding units, and are supported by suitable frame sections 13 (Fig. 2). An endless chain 14' connected to the several traveling winding units, runs on suitable sprocket wheels 15 at opposite ends of the machine, one such sprocket wheel being driven by a motor not shown.

As shown in Figs. 4 and 5 (which are generally similar to Figs. 18 and 15, respectively, of said application Serial No. 386,136), the head portion 30 of the winding units includes a frame element 40 connected to the chain 14' by pivoted link 14'' (Fig. 4) and carrying suitable rollers 41, 42 and 43 adapted to guide the unit along the upper rail 11.

35 A generally vertical frame element 50 extending from the upper frame element 40 down to the lower rail 12 carries a suitable support 52 for the unwinding supply package 53 (Fig. 2) and for the guide wires and tension device which act 40 on the yarn leading from the supply package.

Referring to Fig. 4 a hollow driving head 60 adapted to receive the base of the winding bobbin and having a serrated rim 61 is driven through a shaft 62 from an electric motor indicated generally at 63.

45 A reciprocating traverse rod 66 is driven with a short stroke of traverse (only a small fraction of the length of the final length of the wound bobbin) through cam mechanism also operated by the motor 63. As shown in Fig. 4 the motor shaft 62 carries a worm 70 meshing with and driving a cam wheel 72 through teeth 73 on the periphery thereof. The cam wheel 72 is provided with a double throw cam groove 74 of appropriate shape.

50 Preferably the cam 72, worm 70, and shaft 62

are mounted in a casing 88 secured to the frame element 40, this casing having integral therewith a cup-shaped portion 90 surrounding and holding one end of the motor 63. The traverse rod 66 extends into the casing 88 through a slot (Fig. 4) and inside the casing is connected at its inner end to an arm 91, pivoted at 92 and carrying a cam-follower roller 93 which lies in the cam groove 74.

The outer center 100 for holding the outer end of the filling bobbin is mounted on a plunger 100^a which is slideable in an outboard bracket 100^b, this bracket being fixedly secured to a horizontal bar 100^c rigid with the frame 40 of the winding unit. The outer center 100 is normally forced against the winding bobbin by a spring (not shown) in the bracket 100^b, and may be retracted by a bell crank 100^d of which one arm engages the plunger 100^a within the bracket. When the winding unit reaches the bobbin-changing apparatus of the machine the outstanding arm of the bell crank 100^d engages a stationary angle piece 590 (Figs. 3 and 5) and is moved thereby into the dotted line position of Fig. 4 (as in the case of the two winding units at the left of Fig. 3) thus retracting the center 100 and releasing the bobbin. At the right-hand end of the stationary angle piece 590 (Fig. 3), the bell crank 100^d is released and the plunger 100^a and center 100 return to their normal positions, the center 100 thus engaging an empty bobbin presented to it by a magazine diagrammatically indicated at 112 in Fig. 1. The position of a bobbin held by the magazine is indicated by the center line X—X in Fig. 3, the bobbin being grasped between the centers at this place.

For the purpose of this invention the magazine may be of any suitable construction to supply fresh bobbins to the several winding units in succession, and the magazine may for example have the construction of the magazine 112 of Figs. 2 and 4 of said application, or may embody the improvements as to feeding and delivery of bobbins shown particularly in Figs. 13, 14, 21 and 22 of said application. For simplification of illustration the bobbin magazine is indicated only diagrammatically in this application.

The thread guide assembly T (Fig. 6) is shown as mounted on the reciprocating traverse rod 66 in frictional engagement therewith so as to be movable back and forth with the reciprocating movement of the traverse rod 66 but capable of being slid on the traverse rod 66 so as to be advanced along the traverse rod.

Referring to Figs. 4, 6, 7 and 8, the thread guide assembly T may for example comprise an upper plate 144 above the traverse rod 66 and carrying the eyes 145 and 149 by which the thread respectively enters and leaves the thread guide assembly and a lower plate 150, below the traverse rod 66, these upper and lower plates serving to retain between them vertical spacer members 152, 152, preferably of fiber or other friction material surrounding and frictionally engaging the traverse rod 66. The frictional grip of the thread guide assembly upon the traverse rod 66 is preferably increased by the provision between the two plates 144 and 150, of a tubular jacket 154 of cork or other frictional material surrounding the traverse rod and held in frictional engagement therewith by a surrounding tubular element 155 having springlike fingers 156 (Fig. 8) which hold the cork friction element firmly around the traverse rod 66. A downturned extension 492 on the upper plate of the thread guide assembly carries

5 a guide roller 493 adapted to run loosely in a groove in the horizontal frame member 100c (Fig. 6) thus positioning the thread guide assembly against rotation around its round traverse rod 66.

10 It will be seen from the above description that in a preferred form of the invention there may be employed the general construction of the frame, conveying mechanism, rotary bobbin holding centers and mechanism for opening and closing them to discharge full bobbins and take fresh bobbins that is described in said application, as well as mechanism similar to that described in said application for imparting a short stroke of traverse to the reciprocating thread traversing means on each winding unit.

15 The machine illustrated in this application differs from that of said application Serial No. 386,136 principally in an improvement in the mechanism for determining the progression of the thread traversing means of the several units, as will now be explained.

20 In both the aforesaid patent and application each winding unit was provided with feeler mechanism for causing the thread guide assembly to advance along the traverse rod so as to produce a filling wound bobbin growing from the base to the tip end of the bobbin. In a machine according to the present application, however, such feeler mechanism is rendered unnecessary because the relative movement between the winding units and other parts of the machine is utilized to determine the progressively shifting zones of traverse of the thread traverse means from the base or beginning end of the bobbin to the tip end.

25 Referring to Figs. 1, 2, 3 and 5, the preferred form of mechanism involves a stationary cam-like structure extending around the machine and acting as an abutment to determine the zone of reciprocating traverse of the thread guide assemblies of the several winding units, such that starting at the beginning of winding of a package the zone of traversing is in a relatively short zone near the base end of the bobbin and then is progressively shifted along the bobbin until it finally reaches nearly the tip end of the bobbin.

30 Referring to Figs. 4, 5, 6 and 7, the thread guide assembly T preferably carries on its upper plate 144 an upstanding post 170 having thereon a roller 171. During the travel of the winding units around the machine the zone of traverse of roller 171 and hence of the thread guide assembly T is determined by a non-traveling cam-like structure preferably consisting of two vertical flanges 600 and 601, spaced apart 35 a distance such that travel of roller 171 from one such flange to the other will produce the desired length of traverse stroke of the thread guide assembly. The distance between these flanges 600 and 601 may for example be such amount as 1 inch, 1½ inches, 1¾ inches, 2 inches, or the like, depending upon the desired length of stroke of traverse.

35 Referring to Figs. 1 and 3 it will be observed that, starting at the line Y—Y where the regular stroke of traverse begins, these two flanges 600 and 601 are located adjacent to the base or butt end of the winding bobbin; and that proceeding around the machine in the counterclockwise direction of travel of the winding units, 40 these flanges 600 and 601 are gradually located farther and farther away from the base or butt of the bobbin and nearer to the tip end thereof, finally attaining, at about the line Z—Z, a position adjacent to the tip end and quite removed 45 from the base or butt end. The zone of trav-

erse of the thread guide assembly of each winding unit is determined by the position of the unit on the track.

Thus the typical filling wind is produced, with the yarn laid in many nested conical layers and with the final such conical layer several inches away from the first layer of winding and from the base or butt end of the bobbin.

It will be observed that this principle of using the relative travelling movement between the winding units and other parts of the machine to determine the progressive advance of the zone of winding of the filling wound bobbin greatly simplifies the construction of each winding unit. No feeler mechanism is needed on any of the winding units to govern the advance of the thread guide assembly. And without such feeler mechanism should the yarn break during the winding, there is no possibility of the feeler chafing the body of yarn that was wound prior to breakage. Accordingly, no detector-controlled stop mechanism is needed on the several units.

At the line Z—Z at which place the winding of each successive bobbin has been completed, the machine preferably includes means similar to that described in said application Serial No. 386,136 to return the thread guide assemblies of the successive units to the base or butt end position in aid of associating the thread extending from thread-guide eye 149 with the hollow center 60. Such means can in the present machine conveniently comprise an inclined extension 473 of the outer flange 601 adapted to act upon the roller 171 to carry the thread guide assembly from the final outermost position to a position where the traverse assembly lies near the inner hollow center 60. This extension 473 is preferably continued parallel to the path of travel of the winding units, as shown in Figs. 1 and 3, in the zone where the bobbin magazine 112 is encountered. Then, after the bobbin magazine has been passed, a further inclined guide extension 473a comprising two downturned flanges relatively close together is adapted to receive the roller 171 of each unit, and lead it and the thread guide assembly into position for the thread guide to distribute the thread in the form of a bunch on the bobbin while the roller 171 passes from the line B—B to the line Y—Y (Fig. 3). During this winding of a bunch the motion of the thread guide assembly is preferably restrained by the guide extension 473a to a short stroke consisting of only a fraction of the stroke of reciprocation of the traverse rod 66. Finally when the line Y—Y is reached, the bunch then being complete, the motion of the thread guide assembly passes under control of the two flanges 600 and 601 spaced apart as described above by an amount such that the thread guide can make its full stroke of traverse for winding a filling wound bobbin.

In the preferred form of the invention illustrated herewith where the abutment which controls the progression of the zone of traverse is in the form of a pair of flanges 600 and 601, the inner flange 600 imparts the progressively advancing movement to the thread guide and the outer flange is available to preclude any undesired movement of the thread guide outwardly beyond its intended zone of traverse.

We claim:

1. A winding machine having therein, in combination, a plurality of filling winding units each including a thread-traversing means, an abutment for cooperating with said plurality of fill-

ing winding units, and means for causing a relative traveling movement between said plurality of filling winding units and said abutment, said abutment being shaped and located to act on the 5 thread-traversing means of the several units to define a progressive shifting of the zone of traverse from the base to the tip of the filling winding package during said relative traveling movement.

10 2. A winding machine having therein, in combination, a plurality of filling winding units each including a traversing thread guide and a reciprocating driving element for the thread guide, the thread guide having a frictional connection with said reciprocating driving element, an abutment for cooperating with said plurality of filling winding units, and means for causing a relative traveling movement between said plurality of filling winding units and said abutment, said abutment being shaped and located to act on the 15 thread guides of the several units to define a progressive shift of the zone of traverse thereof from the base to the tip of the filling winding package during said relative traveling movement.

20 3. A winding machine having therein, in combination, a plurality of filling winding units each including a thread guide and means for reciprocating the thread guide, an abutment for cooperating with said plurality of filling winding units, and means for causing a relative traveling movement between said plurality of filling winding units and said abutment, said abutment comprising portions between which the said thread guide moves back and forth during said relative traveling movement, said portions being shaped and located to define a shifting zone of traverse, progressively shifting from the base to the tip 25 of the filling winding package during said relative traveling movement.

30 4. A winding machine having therein, in combination, a plurality of filling winding units each including a thread guide and means for driving the thread guide to impart to the winding thread its short component of traverse in winding a filling 35 wound package, the thread guide being movable with respect to its driving means to permit progression of the zone of traverse, an abutment adapted to cooperate with the thread guides of the several filling winding units, and means for causing a relative traveling movement between said plurality of filling winding units and said abutment, said abutment being shaped and located to control the progression of the thread guides on the several units from the base to the tip 40 of the filling winding package during said relative traveling movement.

5. A winding machine having therein, in combination, a plurality of filling winding units each including a traversing thread guide and means for driving the thread guide to impart to the winding thread its short component of traverse in winding a filling wound package, the thread guide being movable with respect to its driving means to permit progression of the zone of traverse, means for 45 conveying the plurality of filling winding units in a procession, and a stationary abutment adapted to cooperate with the thread guides of the several filling winding units, said abutment being shaped and located to control the progression of the thread guides on the several units from the base to the tip 50 of the filling winding package during said relative traveling movement.

60 6. A winding machine having therein, in combination, a plurality of filling winding units each including a traversing thread guide and means for driving the thread guide to impart to the winding thread its short component of traverse in winding a filling wound package, the thread guide being movable with respect to its driving means to permit progression of the zone of traverse, means for conveying the plurality of filling winding units in a procession, and a stationary abutment adapted to cooperate with the thread guides of the several filling winding units, said abutment being shaped and located to control the progression of the thread guides on the several units from the base to the tip 65 of the filling winding package as the winding units travel.

EDWARD J. ABBOTT.
WINTHROP L. PERRY.
